UNITED STATES PATENT OFFICE.

NORMAN M. BARKER, OF WEST PARK, OHIO, ASSIGNOR, BY MESNE ASSIGNMENTS, TO THE AMERICAN AUTOMATIC CONNECTOR COMPANY, OF WYOMING, DELAWARE, A CORPORATION OF DELAWARE.

SUPPORT FOR AUTOMATIC TRAIN-PIPE CONNECTERS.

Application filed April 11, 1921. Serial No. 460,291.

To all whom it may concern:

Be it known that I, NORMAN M. BARKER, a citizen of the United States, residing at West Park, in the county of Cuyahoga and State of Ohio, have invented a certain new and useful Improvement in Supports for Automatic Train-Pipe Connecters, of which the following is a full, clear, and exact description, reference being had to the accompanying drawings.

This invention relates to automatic train pipe connectors and is primarily concerned with an improvement in the means for supporting a coupler head on the drawbar of a car.

My improved supporting means is shown incorporated with a form of automatic connector, having a spring pressed coupler head mounted on a supporting bracket which is suspended from the drawbar of a car. Such a connector is shown, for example, in Patent No. 1,161,403, issued November 23rd, 1915, to A. L. Moler and his assignees. In this patent the connector bracket is rigidly secured to the drawbar at a point adjacent the drawbar head.

The usual practice for supporting a coupler head, as above explained, is feasible when the drawbar locking mechanism is positioned above the draft rigging, because of the fact that sufficient space is provided beneath the drawbar for attaching a supporting bracket. Occasionally, however, this locking mechanism is positioned beneath the draft rigging and adjacent the locking face of the drawbar and under such conditions, there is not sufficient clearance beneath the drawbar for attaching the supporting bracket, without interfering with the operation of the locking mechanism.

Accordingly, one of the objects of my invention is the provision of means for effectively supporting a connector, so that the operation of any drawbar locking mechanism, which may be positioned beneath the drawbar, will not be impaired.

Another object is the provision of supporting means which shall constitute a rigid structure, that possesses sufficient strength to withstand the stresses incident to coupling the cars, and which is adapted to be incorporated with the connector mentioned in the above patent without necessitating expensive changes.

In carrying out my invention I employ a supporting bracket, which extends away from the connector shank and is secured to the drawbar at a point adjacent the innermost end thereof. Furthermore, I provide a tie which connects the bracket with the drawbar at a point adjacent the outermost end thereof, whereby a three point engagement is effected between the bracket and the draft rigging.

The means for accomplishing the above objects will be more fully set forth in the following description, which relates to the drawings, and the essential characteristics of my invention will be set forth in the claims.

In the drawings, Fig. 1 is a side elevation of two railway cars coupled together and employing an automatic connector embodying features of my invention; Fig. 2 is an elevation of the supporting mechanism shown apart from the railway cars; Fig. 3 is a bottom view of the supporting bracket projected downwardly from Fig. 2; Fig. 4 is a section taken on the line 4-4 in Fig. 2; Figs. 5 and 6 are details showing the construction of the lowermost portion of the supporting bracket.

Designating the parts shown in the drawings by the use of reference characters, A and B represent railway cars which are coupled together by the train couplers C and D and which are provided with conduits as at E, F and G. These conduits may be used for the air signal, the air brake and the steam line respectively.

Positioned beneath the train couplers, I have shown an automatic connector having a head 10 and provided with orifices for receiving the above mentioned conduits. Each head is shown as secured to a shank 11 and supported on trunnions 12 by a bracket 13. A strong spring 14 extends between the bracket and the head, to urge the connector heads into engagement with each other; it being understood that such springs are compressed when the cars are coupled together.

Referring now to Fig. 2, the drawbar C is shown as provided with a locking mechanism, indicated generally at 15 beneath the locking face, which locking mechanism extends rearwardly and requires considerable space for the effective operation thereof.

Accordingly in adapting an automatic connector to a draft rigging which is equipped with this form of locking mechanism, I have shown a supporting bracket 13 as extending away from the connector shank and secured to the inner portion of the drawbar. A preferred way of connecting the bracket to the drawbar is embodied in a through bolt 35 which may extend through the drawbar for permitting the bracket to be pivoted about such point of connection. Beneath this point of connection, I provide a pair of set screws, as at 17, to secure the bracket to the drawbar and to adjust it to various sizes of draft rigging. This bracket preferably comprises a casting, having longitudinal reinforcing ribs 18, which extend from the point of engagement with the drawbar, to the point of engagement with the trunnion 12, and having flanges 19 extending laterally from the ribs and positioned on the upper side of the bracket.

The lowermost portion of the bracket, as is shown in the above patent, is provided with a pair of arms 21 each having a slot 20 for receiving the trunnions 12. The space between the arms 21 is sufficient to permit the shank 11 to have universal movement therein, to compensate for movements of the car when the connector are coupled together.

To provide a three point engagement between the bracket and the drawbar, I employ a connecting tie 25, which is shown as a rod having one end thereof pivoted at 26 to a member 27. This member is preferably an eye bolt which is arranged to be held in threaded engagement with the drawbar. The lower portion of the tie 25 is shown as being adjustably secured to the bracket 13 by means of suitable lock nuts 28, 29, which engage the bracket on the upper and lower portions thereof respectively. In place of the connecting tie, I may provide an arm which comprises a part of the bracket casting, but the preferred form of construction is embodied in the separate member, as above explained.

When two railway cars, equipped with a connector embodying features of my invention, are coupled together, then the stresses incident to such coupling action are transmitted to the drawbar by compression through the bracket 13. Furthermore, the position of the connecting tie provides a reinforcing means which serves, not only to transmit coupling stresses to the drawbar, but also to prevent the bracket from pivoting about the drawbar, in the event of any loosening of the locking nut 17.

In connecting the bracket 13 to the drawbar, it is possible to adjust the height of the connector head by swinging the bracket about the pivot 35 and then rigidly securing it in such adjusted position by regulating

the adjusting screws 17, and the locking nuts 28 and 29. This form of supporting mechanism provides a flexible device which is adapted for use in connection with various sizes of draft rigging, and is also adapted for use in regulating the height of the connector head.

From the foregoing description, it will be seen that I have provided an effective means for supporting an automatic connector head beneath the draft rigging of a car, and for enabling such connector head to be operated without interfering, in any manner, with the operation of any locking mechanism, which may be positioned beneath the drawbar head. Furthermore, it will be seen that I have provided a supporting mechanism which is quite simple in construction and which is capable of being adjusted for various sizes of draft rigging and is well adapted for use in connection with existing forms of connectors.

Having thus described my invention, I claim:

1. In a train pipe connector, a drawbar, a bracket supported on said drawbar, a reinforcement for the bracket supported on said drawbar, the points of support being spaced, and an adjustable connection between the bracket and reinforcement.

2. In a device of the class described, the combination with a drawbar, of a bracket having parallel portions and an inclined connecting portion, and a separate member extending downwardly from the drawbar and rigidly and adjustably secured to the inclined portion of the bracket.

3. In an automatic train pipe connector, the combination with a coupler, of a bracket depending therefrom, said bracket inclining toward the coupler head, and a tie rod pivoted at the underside of the drawbar, and means for adjustably connecting the tie rod with the inclined portion of the bracket.

4. In an automatic connector, the combination with a drawbar, a connector head positioned beneath the drawbar, a bracket comprising an inclined member having the lower end thereof arranged to support the head and having the upper end thereof rigidly secured to the drawbar, a tie rod and means for adjustably securing one end of the tie rod to the bracket, and means for pivotally securing the other end of the tie rod to the drawbar.

5. In a device of the class described, the combination with a drawbar, of a connector head positioned therebeneath, a bracket having the upper end thereof secured to the drawbar and the lower end thereof adapted to support the connector head, and a tie rod having one end thereof adjustably secured to the lower part of the bracket and having the other end thereof secured to the drawbar.

6. In combination, a drawbar, a connector head, a bracket having one end thereof secured to the drawbar, and the other end attached to the head, a separate tie rod carried at its upper end by the drawbar and at its lower end extending through the bracket adjacent the head, and means on the tie bar for adjustably clamping it to the bracket.
- 10 7. In an automatic train pipe connector, the combination with a coupler, of a bracket depending therefrom, a connector head and shank supported by the bracket, an eye secured to the under side of the drawbar, and a tie rod pivoted to said eye, and means for adjustably connecting the tie rod with the lower portion of the bracket.
- 15 8. In combination, a connector head, a bracket therefor, means to support the bracket above said head, a separate rigid member secured to and extending upwardly from the bracket, and means for securing the upper end of said member to the supporting surface, whereby the supporting surface, bracket and member, form a triangle, and means for adjusting the effective length of said member.
- 20 9. In a device of the class described, the combination with a drawbar, of a connector
- 25 head, a supporting bracket therefor, said bracket comprising an inclined member having the ends thereof secured to the drawbar and to the connector head respectively, and a tie member having the upper end thereof secured to the outer portion of the drawbar and the lower end thereof passing through an opening in the bracket, said member extending at substantially right angles to the inclined portion of the bracket, and nuts on said member engaging upper and under surfaces of the bracket, for adjusting the position of said bracket with relation to said member.
10. In a device of the class described, the combination with a drawbar, of a connector head positioned therebeneath, a bracket having the upper end thereof bifurcated and embracing the drawbar, and the lower end thereof adapted to support the connector head, and a tie rod having the lower end thereof passing through and adjustably secured to the lower portion of the bracket and having the other end thereof pivoted to the drawbar.

In testimony whereof, I hereunto affix my signature.

NORMAN M. BARKER.
